UNITED STATES PATENT OFFICE.

MAURICE A. SMITH, OF JEANNETTE, PENNSYLVANIA, ASSIGNOR TO MCKEE GLASS COMPANY, OF JEANNETTE, PENNSYLVANIA, A CORPORATION OF PENNSYLVANIA.

DESIGN FOR A GLASS ARTICLE.

50,590.

Specification for Design.

Patented Apr. 10, 1917.

Application filed December 30, 1916. Serial No. 139,973. Term of patent 3½ years.

To all whom it may concern:

Be it known that I, MAURICE A. SMITH, a citizen of the United States, and residing at Jeannette, in the county of Westmoreland, State of Pennsylvania, have invented a new, original, and ornamental Design for a Glass Article, of which the following is a specification, reference being had to the accompanying drawing, forming part thereof, in which—

Figure 1 is a side view, and Fig. 2 is a

bottom plan view showing my new design applied to a glass article, the shape of which is not novel and is not herein claimed.

I claim:

The ornamental design for a glass article of manufacture, as shown.

MAURICE A. SMITH.

Witnesses:

ROBT. D. TOTTEN,

JOHN F. WILL.
